UNITED STATES PATENT OFFICE

ARVILLE E. McCURDY, OF CLARENDON, VIRGINIA

BEZEL

Application filed March 30, 1931. Serial No. 526,437.

This invention relates to improvements in bezels and particularly bezels of the generally rectangular or non-round type. It is not practicable to mount crystals in bezels of this shape in the manner in which round crystals are mounted, that is, by slightly cupping the crystal under pressure so as to contract its periphery to the size at which it will snap into the rabbet in the bezel. In non-round bezels, for wrist watches and the like in particular, cement has therefore been relied upon to secure the crystal in the bezel. This expedient has proved unsatisfactory, since from various causes the cement loses its bond and the crystal falls out.

The present invention provides a construction in which small spring pawls concealed within the rim of the bezel and retractable to permit the seating of the crystal in the rabbet of the bezel are arranged automatically to project themselves slightly over the edge of the crystal so as to hold the latter securely in place. Cement if used in conjunction with the spring pawls is employed only to provide a dust-proof seal between the crystal and bezel and not essentially as an auxiliary retaining means for the crystal which is firmly held in place through the instrumentality of the spring pawls alone.

In the drawings in which the same characters of reference have been employed throughout the several figures to designate identical parts:

Figure 1 is a perspective view in separated relation, of the bezel and a crystal, of the shape to which my invention may be particularly advantageously applied;

Figure 2 is a bottom plan view of the bezel;

Figure 3 is a top plan view, a part being shown in section;

Figure 4 is a side elevation on an enlarged scale of one of the springs;

Figure 5 is a cross section illustrating the method of inserting the crystal in a bezel embodying the principles of the present invention; and

Figure 6 is a cross section taken at right angles to Figure 5, with spring pawl shown in front of the crystal.

Referring now in detail to the several figures, the numeral 1 represents in general a bezel of non-round shape having an interior peripheral rabbet 2 on which the edge of the crystal 3 is adapted to seat. The edge of the crystal is preferably bevelled. Ordinarily, in a bezel of this shape, the crystal would be cemented in place. In the present construction retractable spring pawls 4 and 5 extend over the lower edge of the bevel of the crystal and bear against the sloping surface of said bevel as illustrated at the left hand side of Figure 5.

Figure 2 shows that the bezel is provided on its under surface with a channel 6. In carrying out my invention the side wall 7 of the rabbet is formed with slots 8 and 9 extending lengthwise on opposite sides of the bezel and communicating with the channel 6. The spring pawls 4 and 5 are suitably anchored in the channel 6 as by means of screws 10 and the resilient free ends of said pawls are so bent as to lie in the slots 8 and 9 and to extend slightly beyond the inner sides of said slots so as to project within the "sight" of the bezel. It will be observed from Figure 5 that the projecting portions of the springs lie above the plane of the horizontal shoulder of the bevel on which the crystal rests.

When inserting the crystal in the bezel, the crystal is slightly tilted as shown in Figure 5, until the lower edge of the bevel on one side rests upon the horizontal shoulder of the rabbet and the crystal is then pushed against the adjacent spring pawl forcing the latter backward until the lower edge of the bevel of the crystal on the opposite side rests upon the projecting spring pawl on said opposite side. A suitable instrument such as is indicated at 11 in Figure 5 is then pressed against the spring pawl upon which the crystal rests, retracting said pawl until its support is withdrawn and the crystal falls upon the rabbet. The spring pawl then automatically springs outwardly against the sloping face of the bevel and the crystal is thus firmly held in place on both sides.

The sloping nature of the bevel of the crystal assures not only that the crystal is held in place by the engagement of the spring

pawls but that it is pressed firmly against the horizontal shoulder of the rabbet thus avoiding any looseness of the crystal.

Since it is customary to have the side wall 5 of the rabbet somewhat inclined so that the rabbet is under-cut it suffices to have the spring pawl on one side only of the bezel if desired, since the pressure of the spring will force the opposite bevelled edge of the crystal 10 beneath the overhanging wall of the bezel. The use of spring pawls on opposite sides of the bezel is however preferred.

It is to be understood that while I have disclosed what I believe to be a preferred and 15 practical form of the invention, the details of construction as illustrated and described are merely by way of example and not to be construed as limitative in their bearing upon the scope of the invention as claimed.

20. What I claim is:

1. Bezel comprising a frame having a rabbet for receiving a crystal, a side wall of said rabbet being slotted, and yielding means projecting slightly through the slot in said rabbet for frictionally engaging an adjacent edge of said crystal and holding it in place.

2. Bezel comprising a frame having a rabbet for receiving a crystal having a bevelled 30 edge, a side wall of said rabbet being slotted, and yielding means projecting through the slot in said rabbet a slight distance above the base of said rabbet for engaging the sloping face of the adjacent edge of said crystal, for holding said crystal in place.

3. Bezel comprising a frame having a rabbet for receiving a crystal, and formed with an annular channel back of the side wall of said rabbet, said side wall having a slot opening into said channel, and a spring pawl 40 fixed in said channel and extending through said slot for frictionally engaging an edge of the crystal.

4. Bezel comprising a frame having a rabbet for receiving a crystal having a bevelled edge, and formed with an annular channel back of the side wall of said rabbet, said side wall being formed with an opening into said channel, a spring pawl having a portion fixed 50 in said channel, and a free resilient portion extending through said slot above the base of said rabbet in a position yieldingly to engage the sloping face of the bevelled edge of said crystal.

55. In testimony whereof I affix my signature.
ARVILLE E. McCURDY.
